PERCUSSIVE CAP STRUCTURE

John W. Ryan, 11027 Cashmere St., Bel-Air, Calif.
Filed Feb. 9, 1959, Ser. No. 791,983
4 Claims. (Cl. 102—86.5)

This invention relates to a percussive cap structure for use particularly in a toy gun.

This invention provides for a percussive cap for use in a single shot or repeating cap pistol, which can be pre-cut to a desired configuration, preferably circular, and held on a strip or sheet of paper or other suitable material by pressure-sensitive adhesive means until removed therefrom for use in the cap pistol or optionally for use while still adhered to the strip or sheet. This invention embraces the use of a pressure-sensitive adhesive material either on the cap itself, or on the backing sheet or strip, whereby, in one form, the cap having a pressure-sensitive adhesive material on one of its faces is self-retaining on the anvil, or optionally on the hammer, of the toy pistol to be fired as by striking thereof by the hammer of the pistol; or, in another form, the sheet or strip having a pressure-sensitive adhesive material holding the caps thereto is retained on the anvil of the toy pistol by means inherent with the pistol; or, in yet another form, the pre-formed cap may be separated from a strip having a pressure-sensitive adhesive material on a face thereof and held on the anvil of the pistol by any suitable means provided in the pistol.

In its preferred embodiment, the invention provides a sheet having pressure-sensitive adhesive material secured on one surface thereof, and one or more charges of fulminating material, such as gun powder or the like, secured to the opposite face of the sheet and a circular, endless cut made through the sheet, encircling the fulminating material, whereby the portion of the sheet inside the circular cut and having the charge thereon may be removed from the sheet for self-securement to the anvil of the toy pistol.

Toy pistols, in the past, have been formed with various types of anvils, the more common of these being a flat seat formed integral with the body of the pistol against which the hammer strikes to fire the cap, a revolving anvil having a flat side or outer peripheral surface engageable by the hammer of the pistol, or a removable simulated cartridge having a flat end engageable by the hammer of the pistol. Any of these anvils are suitable for the use of an explosive cap in accordance with this invention. To achieve greater realism, children now prefer to simulate actual loading conditions which is, in reality, an action involving loading individual explosive cartridges within the chamber of the gun. To simulate such action, an individual cap is preferred. However, such individual caps have in the past been cumbersome to handle, to insert into the gun, and to store. Handling of such caps frequently results in spilling or dropping thereof with defacing or loss thereof.

It is therefore an object of this invention to provide a new and improved percussive cap structure in which an individual cap, having a fulminating charge incorporated therein, is easily and securely stored until use, is easily and quickly accessible for use and easily insertable into a toy gun for detonating of the charge by the striking action of the hammer of the gun.

Another object of this invention is to provide a new and improved cap structure in which the individual charges may be secured to a sheet or strip in any desired spacing and used by feeding the strip or sheet on the anvil in any suitable manner provided within the gun.

A further object of this invention is to provide a new and improved percussive cap structure which is economical to manufacture and capable of mass production.

2

A general object of this invention is to provide a new and improved percussive cap of the character described which overcomes disadvantages of prior means and methods heretofore intended to accomplish generally the same purpose.

These and other objects of this invention will be more apparent from the following drawings, detailed description and appended claims.

In the drawings:

10 FIG. 1 is an enlarged fragmentary view, in perspective, of a cap structure designed and constructed in accordance with this invention;

15 FIG. 2 is a vertical, cross-sectional view as taken substantially along a line 2—2 of FIG. 1;

15 FIG. 3 is an enlarged perspective view of an individual cap forming a part of the structure illustrated in FIG. 1, with a portion thereof broken away for greater clarity;

20 FIG. 4 is a fragmentary view, illustrating one application of the cap structure of the instant invention, with parts broken away for greater clarity; and

FIG. 5 illustrates another application of this invention;

FIG. 6 is a fragmentary perspective view illustrating yet another application of this invention.

Referring more particularly to the drawings, there is shown, by way of illustration but not of limitation, a cap structure generally referred to by the numeral 10 and designed and constructed in accordance with this invention. The cap structure 10 comprises a sheet 11 of relatively flexible or semi-rigid material, such as paper or the like, juxtaposed to a second sheet 12, of similar material, in face-to-face relationship.

The first sheet 11 is removably secured to the second sheet 12 by a pressure-sensitive adhesive material 13 provided on an adjacent face of at least one of the sheets

35 11, 12 for temporarily securing one sheet to the other. As used hereinafter in this specification and in the claims, the term "pressure-sensitive adhesive" shall be deemed to refer to an adhesive material that readily adheres to a surface against which it is pressed but which may be readily separated therefrom by pulling and without tearing or damage to the members held together thereby. Such pressure-sensitive adhesives are well-known and need not be described in further detail.

The sheet 11, as herein illustrated, is provided with at least one, and preferably a plurality of charges 14 of a fulminating material, such as commonly used in toy caps and comprising a chlorate-sulphide-phosphorous compound or the like. The charges 14 are secured in spaced relationship on the sheet 11 as by an upper sheet 16 of a relatively thin flexible material, such as paper or the like, secured permanently to the sheet 11 as by a permanent adhesive. The sheet 16 is secured against the sheet 11 at portions 17 surrounding the charges 14 thereby to completely enclose the charges 14 and sandwich them between the sheet 16 and 11 within pockets 18 formed therebetween. The pockets 18 may be optionally pre-formed, if desired, or formed during the operation of securing the sheet 17 to the sheet 11, the sheet 16 being substantially more flexible than the sheet 11 and thereby forming a bulge, as best seen in FIGS. 2 and 3.

An endless cut 20, preferably circular in configuration, is formed around each charge 14 and spaced therefrom and extending through the sheet 16 and 11 to form discrete cap units referred to by the numeral 19, each unit being removable from the sheet 12 as by lifting of one edge thereof and peeling away from the sheet 12, as indicated by cap 19' of FIG. 1.

The pressure-sensitive adhesive material 13 is preferably secured to the face 21 of the sheet 11, opposite the face 22, upon which the charges 14 are secured. In this manner, discrete cap units 19 removed from the sheet 11 retain the layer of pressure-sensitive adhesive material

13 secured thereto, whereby the cap unit 19 may be secured, by pressing, to any suitable anvil of a toy pistol for detonation of the charge 14 by the striking force of a hammer of the pistol against the anvil. Each sheet may be optionally provided with pressure-sensitive material on adjacent faces, if desired.

Referring to FIG. 4, a portion 23 of a pistol is shown having an anvil 24 integral with the pistol and having a relatively flat face 25 on which a cap unit 19 may be temporarily secured by pressing the cap unit 19 on the face 25 with the pressure-sensitive adhesive material in contact with the face 25 and aligned with the hammer 26 of the gun. Actuation of the hammer 26 to strike an anvil 24, causes the charge 14 embedded between the sheets 11 and 16 to detonate.

If desired, the pressure-sensitive material may be secured to the sheet 12, whereby cap units removed therefrom retain little if any of the adhesive material. In the instant form, a cap identical to the cap 19 but without pressure-sensitive adhesive material, may be inserted into a conventional cap-retaining means illustrated in broken lines 27 of FIG. 4 for positioning the cap in the path of the hammer 26 to detonate the charge. The cap 19 may be optionally stuck to the striking face of the hammer if desired, for firing thereof against the anvil.

Referring to FIG. 5, an anvil 31 is illustrated in the form of a simulated cartridge. The cartridge includes a shell 32 provided with a flat end 33 to which a cap unit 19, having pressure-sensitive adhesive material 13 secured to the face 21, as previously described, may be adhered for detonation of the charge 14 thereof as by a hammer, similar to the hammer 26 of FIG. 4.

As illustrated in FIG. 6, cap units 19, having pressure-sensitive adhesive material 13 secured thereto, may be spaced on a strip 34 of paper, or other suitable material, for storage of the caps 19 thereon or optionally for feeding of the caps 19 in any predetermined spaced relationship over an anvil of the rotating or other type.

To facilitate removal of the caps 19 from the structure 10, the sheet 11 or 12 which does not have the pressure-sensitive adhesive material secured thereto preferably includes a glossy surface adjacent the juxtaposed sheet to prevent excessive adherence thereto.

While I have herein shown and described my invention in what I have conceived to be the most practical and preferred embodiments, it is recognized that departures may be made therefrom within the scope of my invention, which is not to be limited to the details disclosed herein but is to be accorded the full scope of the claims so as

to embrace any and all equivalent devices and methods.

What I claim as new and desire to secure by Letters Patent is:

5 1. A percussive cap structure comprising: a carrier sheet; spaced charges of fulminating material on one face of said sheet; an exposed outside layer of adhesive on the opposite face of said sheet; and cuts extending through said sheet, each of said cuts substantially surrounding one of said charges and being spaced therefrom.

10 2. A percussive cap for adhesive mounting on an anvil for firing, comprising: a first sheet having an exposed outside layer of adhesive material on one surface thereof; a charge of fulminating material on an opposite surface of said first sheet and spaced from the periphery of said 15 first sheet; and a second sheet overlying said opposite surface of said first sheet and said charge and having peripheral portions secured against said opposite surface and enclosing said fulminating material in sandwiched relationship to said first sheet.

20 3. A percussive cap structure for adhesive mounting on an anvil for firing, comprising: a pair of sheets juxtaposed in face-to-face relationship; a pressure-sensitive adhesive material on a face of one of said sheets for temporarily and removably securing said sheets together, one to the other; and a plurality of spaced charges of 25 fulminating material secured to a face of at least one of said sheets, said one of said sheets having an equal plurality of cuts extending therethrough, each of said cuts substantially surrounding one of said charges and being spaced therefrom.

30 4. A percussive cap structure for adhesive mounting on an anvil for firing, having a supporting sheet and a centrally positioned fulminating charge on one face thereof, an exposed layer of pressure-sensitive adhesive on the other face of said sheet whereby said cap may be placed and removably held in a desired position on an anvil, and a cover sheet overlying said other face and temporarily adhering to said adhesive whereby it may be removed to expose said adhesive.
